UNITED STATES PATENT OFFICE

150,440

DESIGN FOR AN EVAPORATIVE COOLER CASING

Oscar C. Palmer, Phoenix, Ariz.

Application April 22, 1947, Serial No. 138,532

Term of patent 14 years

(Cl. D62—4)

To all whom it may concern:

I, Oscar C. Palmer, a citizen of the United States, residing in Phoenix, in the county of Maricopa and State of Arizona, have invented a new, original, and ornamental Design for an Evaporated Cooler Casing of which the following is a specification, reference being had to the accompanying drawings forming a part thereof:

Figure 1 is a top plan view of an evaporative cooler casing embodying my new design.

Figure 2 is a front elevational view thereof;

Figure 3 is a side elevational view thereof; and

Figure 4 is a perspective view thereof.

I claim:

The ornamental design for an evaporative cooler casing, substantially as shown.

OSCAR C. PALMER.
